UNITED STATES PATENT OFFICE.

EDWARD THOMAS RODNEY COATES AND JOSEPH GORDON COATES, OF
MATAKOHE, NEW ZEALAND.

TRENCHING AND DITCHING PLOW.

No. 800,075.

Specification of Letters Patent.

Patented Sept. 19, 1905.

Application filed February 17, 1903. Serial No. 143,870.

To all whom it may concern.

Be it known that we, EDWARD THOMAS RODNEY COATES and JOSEPH GORDON COATES, farmers, subjects of His Majesty the King of the United Kingdom of Great Britain and Ireland, residing at Matakohe, in the Provincial District of Auckland and Colony of New Zealand, have invented a certain new and useful Improved Trenching and Ditching Plow, of which the following is a specification.

This invention relates to a trenching or ditching-plow; and the purpose of the same is to provide a simple and effective organization of elements whereby the plow may be operated to trench or ditch deeper than is done at present by other plows by making three following cuts in the same furrow. This is accomplished by having the moldboard increased in size or made larger than in ordinary plows and suitably curved, the operation of the plow being rendered more effective by means of an elongated share and auxiliary staggered and beveled wheels hereinafter described.

The invention also consists in the details of construction and arrangement of the several parts, which will be more fully hereinafter set forth.

In the drawings, Figure 1 is a side elevation of plow embodying the features of the invention. Fig. 2 is a transverse vertical section on the line 2 2, Fig. 1. Fig. 3 is a view similar to Fig. 2 with beveled-wheel attachments and their supporting means added. Fig. 4 is a detail perspective view of a portion of the plow.

Similar characters of reference are employed to indicate corresponding parts in the several views.

The moldboard A is enlarged and has its front upper edge B curved downwardly and inwardly to the point where it commences to concave toward the share and its upper end C curved regularly to meet the outer edge portion. In other words, the curvature of this moldboard is such as to better facilitate the outthrow of the earth or soil and also to render the operation of ditching with the improved plow more effective. The share D is somewhat longer to correspond to the enlarged size of the board A, and the lower rear end portion of the board A extends downwardly at the back end of the share D to have the edge thereof meet with the lower

edge of the share. The moldboard and share 55 or plow proper is secured to beam E, the latter being shaped to carry a double horseshoe clasp or yoke F, which has a plurality of openings or holes G formed therein for raising and lowering it on the said beam E. 60 Between the lower curved extremities of the clasp or yoke a colter or disk cutter H is concentrically fitted and held by a spindle a, which has terminal bearing in the lower portion of the clasp or yoke. By means of a clamp 65 N a cross-arm M is secured to the beam E ahead of the cutter H and carries thereon a shank J, which is connected to an ordinary staggered wheel K by a spindle L, said shank being securely held to the cross-arm M. 70 The cross-arm M is long enough to cause the wheel K to be located at a distance outwardly from the plane of operation of the share D and also in longitudinal alinement with the rear portion of the moldboard. In advance of the 75 cross-arm M a shank R is held on the beam E by a clamp T, the lower end of the shank being slightly bent to adapt it to carry a beveled staggered wheel S at the reduced end. This shank R can be adjusted to any depth, and 80 the same is true of the shank J, as shown by Fig. 4, and, furthermore, it will be understood by the use of the clamps N and T the wheels K and S may be adjusted longitudinally on the beam E. The clevis U is longer than the 85 ordinary devices of this class and is formed with more holes in it than usual to provide for a proper depth of adjustment in plowing, and the ordinary shackle V connects therewith for attachment thereto of the draft de- 90 vices.

During the use of the plow in forming a trench the wheel K is raised and lowered as the operation may require, and, furthermore, both wheels will be adjusted longitudinally 95 of the beam and the wheel K inwardly and outwardly with respect to the beam to accommodate the different conditions or classes of work to be performed. The object of having the wheels respectively staggered and staggered and beveled is that they lighten and assist the draft of the plow and said wheels are prevented from working into the ground and clogging the progress of the plow. The plow can be buried by the soil displaced without friction against the bank or land side, which is avoided by the cut of the colter H and the thrust of the beveled wheel S against

the landside. The colter H is purposely made large, so as to cut deeper than usual and to lighten the draft.

The inward and outward movement of the wheel K is accomplished through the adjustment of the clamp P engaging the shank J. It will be understood that the clamps P, N, and T will be of the most approved pattern and those best adapted for the purpose, and many modifications in the cut or cuts made by the plow may be accomplished by adjusting the cutting-colter H and the wheels K and S, as well as through the adjustment of the shackle V of the clevis U. It will also be understood that changes in the proportions and dimensions may be resorted to without departing from the spirit of the invention.

Having thus fully described the invention, what is claimed as new is—

20 In a plow of the class set forth, the combination of an enlarged curved moldboard having an elongated share secured thereto, a beam

to which the moldboard is attached, a cross-arm longitudinally adjustable on the beam in advance of the moldboard and projecting outwardly at one side of the latter, a staggered wheel vertically held on the arm and vertically and transversely adjustable with relation to the latter to modify its depression and distance outwardly with respect to the beam, 25 a beveled staggered wheel adjustably held on the beam in advance of the cross-arm, the first-named wheel having a greater diameter and standing outwardly a greater distance from the beam than the last-named wheel, and a 30 rotating disk cutter adjustably held on the beam close to the front portion of the moldboard.
